1

BACKGROUND OF THE INVENTION

Field of the Invention

The present invention relates to a new and distinct hybrid variety of (Texas Bluegrass×Kentucky Bluegrass)×Kentucky Bluegrass that has been designated as 'HB 329' bluegrass.

(57) **ABSTRACT**

A hybrid variety of (Texas bluegrass×Kentucky bluegrass)×Kentucky bluegrass as described, characterized by a moderately rapid establishment; a light green, dense turf; a wide leaf blade; aggressive rhizome growth; a reduced level of cotton on the seed; and a low to medium-low seed yield potential.

Description of Related Art

A Texas Bluegrass×Kentucky Bluegrass hybrid designated 'Reveille' has been disclosed in PVP Certificate No. 9800337. Another Texas Bluegrass×Kentucky Bluegrass hybrid designated 'HB 129' has been disclosed in pending U.S. patent application Ser. No. 11/197,945, filed Aug. 5, 2005, claiming the benefit of provisional application No. 60/599,446, filed Aug. 5, 2004.

SUMMARY OF THE VARIETY

'HB 329' bluegrass originated as the progeny formed by crossing an interspecific hybrid bluegrass (Texas Bluegrass×Kentucky Bluegrass) designated HB 47 (a female plant 7-23×cv. 'Geronimo' male plant) as the female parent crossed with cv. 'Ascot' Kentucky bluegrass (*Poa pratensis* L.) as the pollen parent. As a result of this breeding, a distinct hybrid variety was produced asexually propagated by rhizomes, tillers and disseminules displaying perfect flowers, apomixis and turfgrass performance characteristics in the F_1 generation.

Interspecific hybrid bluegrass female plant HB 47 is an unreleased plant selected and maintained in Gervais, Oreg. for its tiller density, turf quality and lack of male reproductive organs. 'Ascot' Kentucky bluegrass was bred by The Scotts Company, Marysville, Ohio, and has been disclosed under the designation BA 77-279 Kentucky Bluegrass in U.S. Plant Pat. No. 9,977 P, issued Jul. 22, 1997.

The highly apomorphic seed of 'HB 329' bluegrass was produced first at Gervais, Oreg. This seed was used to plant turf performance evaluation trials and later, seed production fields. The seed of 'HB 329' has been found to be stable. Asexual production of 'HB 329' initially was performed at Gervais, Oreg. by propagules (tillers and rhizomes) and by disseminules (modified caryopses produced by apomixis), and has consistently produced progeny plants indistinguishable from the first generation asexual reproduction of the instant plant. The apomixis level of 'HB 329' is approximately 94%. The apomixis level was determined by examining field planting of 'HB 329' in two years of rating for apomorphic origin and from plants grown in a controlled environment chamber from disseminules harvested over four growing seasons from field grown plants in Gervais, Oreg.

'HB 329' has a number of highly desirable characteristics, including a dark green color, a moderate level of seedling vigor; high sod strength; and shows above average downy mildew and melting out disease tolerance when compared to other hybrid bluegrasses and Kentucky bluegrass varieties. 'HB 329' has an upright leafy turf type growth habit, and a dark green color that can be maintained throughout an entire growing season. 'HB 329' demonstrates very good fall color and very good winter color under mild winter conditions. 'HB 329' has shown good shade tolerance including downy mildew tolerance.

'HB 329' has a moderate amount of cotton (webbing) on the caryopsis. 'HB 329' has a low to medium-low seed yield potential in the Kentucky bluegrass seed production region of the northwestern United States and has shown the potential for economic seed production.

In comparison with the Reveille and 'HB 129' hybrids, 'HB 329' has demonstrated a germination and emergence rate slower than HB 129 but more rapid than Reveille in both fall and spring sowings. 'HB 329' has shown more seed cotton as compared 'HB 129' and has less than 'Reveille'. It is believed that the presence of the cotton on the Reveille seed results in poor seed recovery of this hybrid and causes 'Reveille' to be available predominantly as a vegetatively reproduced product from rhizome and tiller materials.

Texas bluegrass is a vigorous sod-forming perennial native in the Southeastern and Southern Plains States. Plants grow up to 3 feet on strong soil, with numerous leaves 6 to 12 inches long and 0.25 inch wide. The grass grows throughout the winter producing abundant, nutritious pasture which is highly palatable. This is a valuable species where native,

but seeding is difficult. The species is dioecious, with male and female parents. It produces only limited quantities of seed which is covered with woolly hairs that are difficult to remove. Consequently, establishment of stands for agricultural use is limited. Accordingly, Texas bluegrass exhibits similar problems to those encountered with Reveille that are overcome by the present 'HB 329' hybrid.

In comparison with a number of Kentucky bluegrass varieties and with hybrid bluegrass varieties such as HB 129 and Reveille, 'HB 329' has an average to above-average seed size with a lower number of seeds per pound. The width of vegetative leaves of unmowed mature plants of 'HB 329' are of medium to wide. 'HB 329' has a short to intermediate flag leaf length and with fewer hairs on the upper margin of the ligule than 'HB 129', fewer hairs on the collar margin and dorsal side of the leaf sheath than 'HB 129' and Kentucky bluegrasses. 'HB 329' is shorter than 'HB 129' and 'Reveille' hybrid bluegrasses and is similar in plant height to 'Ascot' Kentucky bluegrass. 'HB 329' has fewer florets per spikelet than HB 129 and is similar to 'Reveille' hybrid bluegrass. Anther color is 87% purple and 13% yellow distinguishing 'HB 329' from 'HB 129' which is 100% purple.

BRIEF DESCRIPTION OF THE DRAWING

FIG. 1 is an 'HB 329' panicle;
 FIG. 2 is an 'HB 329' seed; and
 FIG. 3 is an 'HB 329' plant shortly after completing anthesis.

DETAILED DESCRIPTION OF THE VARIETY

'HB 329' (Texas bluegrass×Kentucky bluegrass)×Kentucky bluegrass hybrid which may also be designated as (*Poa arachnifera* Torr.×*Poa pratensis* L.)×*Poa pratensis* L. hybrid is perennial with creeping rhizomes forming a moderately dense turf. When plants overwinter in the field and grow undisturbed by clipping, culms are semi-erect averaging 42.1 cm in length. The vegetative leaf averages 2.7 mm in width. The flag leaf averages 6.35 cm in length, 3.3 mm in width, has a sheath length of 12.35 cm. The flag leaf averages fewer hairs on the ligule than 'HB 129' hybrid bluegrass. The panicle averages 8.2 cm in length. The lowest whorl of the panicle averages 4.4 branches. 'HB 329' has 4.6 florets per spikelet on the 1st whorl and 5.0 florets per spikelet for the 3rd whorl. The lower and upper glumes of the first whorl are 3.7 and 3.6 mm respectively and the lower and upper glumes of the third whorl are 3.6 and 3.7 mm respectively.

For the vegetative leaf, the number of hairs is average for the leaf sheath margin, below average for the dorsal side of the leaf blade, below average for the upper margin of the ligule, and below average for the collar margin compared to other varieties. 'HB 329' differs from the Kentucky bluegrass varieties in regard to such morphological characteristics as seed length and width, culm length, and hairs on the collar margins of the vegetative leaf, on the upper surface of the vegetative leaf, on the ligule of the flag leaf and anther color.

'HB 329' produces inflorescences relatively early compared with Kentucky bluegrasses, and reaches anthesis later than many other Kentucky bluegrass and hybrid bluegrass varieties.

Since environmental conditions such as soil and climate may influence morphological characteristics to some extent,

comparisons of 'HB 329' were made with Kentucky bluegrass varieties and HB 129 hybrid bluegrass under like conditions and the comparisons are set forth in Tables 1-10, as follows.

The seed of 'HB 329' was conditioned by removing most of the extraneous materials that may have been harvested with the seed, such as small pieces of plant stems and leaves, soil particles, seed of other plants and the like. This conditioned seed of 'HB 329' averages 3.16 mm in length, and 0.87 mm in width. 'HB 329' has about 789,565 seeds per pound.

Comparisons of 'HB 329' with 'HB 129' and Kentucky bluegrass varieties in terms of seed length, seed width and 1000 seed weight are shown in Table 11 as follows:

TABLE 11

TABLE 11-continued

Comparison of seed length, seed width and 1000 count seed weight of 'HB 329' and various Kentucky bluegrass varieties and HB 129 hybrid bluegrass for years 1 & 2.

Variety	Seed Length (mm)		Seed Width (mm)		1000 Count Seed Weight (g)	
	Year 1	Year 2	Year 1	Year 2	Year 1	Year 2
America	2.63	0.83	0.470	0.383		
LSD (0.05)	0.4	0.067	0.09	0.074		

'HB 329' has shown reduced seed cotton on conditioned and unconditioned seed compared to Reveille and greater seed cotton compared to HB 129 (Tables 12 and 13). It is thought that the presence of the cotton on seed has led to poor seed recovery and the availability of Reveille predominantly as a vegetatively reproduced product from rhizome and tiller materials.

TABLE 12

Comparison of 'HB 329' to other hybrid bluegrasses for cotton on conditioned seed.

Variety	Seed cotton rating		
	1 - no or little cotton, 2 - scant cotton, 3 - copious cotton	2	1
'HB 329'		2	
HB 129		1	
Reveille		3	

TABLE 13

Comparison of lemma length (eyepiece assisted), lemma cotton length (% of lemma length), lemma cotton length calculation and length of the cotton (eyepiece assisted, 7x) from spikelets harvested (unconditioned seed) from various bluegrass cultivars grown in a greenhouse under controlled environment (average 4 florets subsamples-lower whorl branches) at Gervais, Oregon. Data were collected from three replicates. 'HB 329' showed reduced lemma cotton length (column C) when compared to Reveille hybrid bluegrass and Texas 51-90 Texas bluegrass but greater than HB 129.

Column	Lower Whorl Cotton		Lemma Cotton		Lower Whorl Cotton	
	Length (mm)	Length (mm)	Length (mm)	Length (mm)	Length (mm)	Length (mm)
	Eyepiece (7x)	% of Lemma Length	Length (A) x (B) = C	Length (A) x (B) = C	Eyepiece (7x)	Eyepiece (7x)
Variety	A	B	C	C	D	D
	mm	Percent	mm	mm	mm	mm
'HB 329'	4.8	61.1	2.9	3.1		
HB 129	3.9	49.1	1.9	1.8		
Texas 51-90	5.7	126.1	7.0	6.8		
Reveille	4.4	94.2	4.1	4.1		
Ascot	4.1	52.5	2.2	2.2		
Geronimo	3.8	50.7	2.0	1.9		
LSD (P = 0.05)	0.8	19.3	0.9	0.7		
CV	10.7	15.8	16.2	12.2		

'HB 329' has performed well throughout the U.S. as exhibited by good turf quality ratings under reduced management inputs in comparison with other Kentucky bluegrass varieties and other Texas×Kentucky bluegrass hybrids. In addition, it has a dark green color with moderate turf density that can be maintained throughout the growing season. 'HB 329' shows good fall and winter color compared with most Kentucky bluegrass varieties and HB 129 hybrid bluegrass.

US PP18,439 P2

11

TABLE 14

Comparison of 'HB 329' with Texas bluegrass and various Kentucky bluegrasses and HB 129 hybrid bluegrass.						
Variety	Plant Height (cm)	Longest Rhizome (cm)	Panicle Length (mm)	Flag Leaf Length (mm)	Flag Leaf Width (mm)	Flag Leaf Sheath Length (mm)
'HB 329'	27.3	38.0	63.5	31.2	3.9	53.7
HB 129	41.5	49.0	25.6	25.6	4.0	74.3
Unique	17.3	40.0	34.7	14.2	1.2	48.5
Abbey	37.0	44.0	62.8	21.1	3.5	76.3
Texas bluegrass	80.0	53.3	126.9	97.2	6.4	146.9
Midnight	21.8	36.6	—	—	—	—
Touchdown	39.8	50.0	27.4	27.4	3.6	66.5
Limousine	29.8	40.8	18.9	18.9	3.2	52.5
LSD (0.05)	14.0	9.8	22.2	15.0	0.5	25.8

‘HB 329’ bluegrass has been shown to provide good downy mildew tolerance, good melting out disease tolerance, dark green genetic color and above average winter color (Table 15). ‘HB 329’ bluegrass has been shown to possess good living ground cover in the summer, medium leaf texture and average spring greenup as compared to other bluegrasses (Table 16).

o Denotes significantly lesser or poorer performance than ('HB 329') based on LSD Values

x Denotes significantly greater or better performance than ('HB 329') based on LSD Values

Denotes similar or comparable performance to ('HB 329') based on LSD Values

With regard to a comparative analysis conducted for purposes of determining color of 'HB 329' plants relative to Kentucky bluegrass varieties and a hybrid bluegrass, readings were taken of the vegetative color of 'HB 329' on actively growing plants with adequate nutrient and water availability. Color readings showed that 'HB 329' leaves had a dark green color and has blue-green coloration. This was dissimilar to HB 129 and most Kentucky bluegrasses with the exception of Langara (Table 17).

TABLE 17

Comparison of ratings for growth habit, leaf color and leaf blade width for 'HB 329' and various Kentucky bluegrass varieties and HB 129 hybrid bluegrass for year 2.

Variety	Habit	Leaf Color		
		Green	Blue Green	Blade Width
'HB 329'	2.0	3.6	3.1	2.7
HB 129	2.0	1.0	1.0	4.5
Langara	3.0	3.1	1.9	3.6
Julia	2.1	1.6	1.4	3.2
Adelphia	2.0	2.4	1.8	4.0

1 - Pros-	1 - Light	1 - Not Blue	1 - Very	
trate	Green	Green	Fine	

TABLE 17-continued

Comparison of ratings for growth habit, leaf color and leaf blade width for 'HB 329' and various Kentucky bluegrass varieties and HB 129 hybrid bluegrass for year 2.

Variety	Growth Habit	Leaf Color		
		Green	Blue Green	Blade Width
2 - Semi- Pro- strate	2 - Medium Green	2 - Mod Blue Green	2 - Fine 3 - Medium	
	3 - Mod Dark Green	3 - Blue- Green	4 - Broad 5 - Very Broad	
	4 - Very Dark Green	4 - Strong Blue- Green		

Further comparative testing of 'HB 329' plants relative to Kentucky bluegrass, Texas bluegrass and hybrid varieties was conducted and the results of this testing are set forth in the following Tables 18 and 19:

TABLE 18

Comparison of morphological traits of flowering tillers of plants allowed to over winter in the field and brought into a controlled greenhouse environment (60-75° F.) in late winter and allowed to grow undisturbed during the winter of 2004-2005 at The Scotts Company facility at Gervais, Oregon.

Variety	Flag Leaf Ligule Length (mm)	Flag Leaf		Anthesis (days to flowering)
		0 = none 9 = Many	Thickness (mm)	
'HB 329'	2.3	3.2	0.0182	145
HB 129	1.3	5.8	0.0149	138
Reveille	2.3	0.9	0.0207	141
Geronimo	1.7	7.1	0.0164	140
Ascot	2.0	5.6	0.0166	141
Midnight	0.8	3.9	0.0145	148
Buckingham	2.4	8.1	0.0190	142
Texas Bluegrass (TX 51-90)	1.7	0.1	0.0262	140
Texas Bluegrass (TX 39-88)	2.7	0.1	0.0199	
Texas Bluegrass (TX 49-90)	2.0	0.5	0.0231	140
Kelly	2.1	6.3	0.0163	143
LSD (P = .05)	0.663	1.93	0.003324	4.854

'HB 329' has a similar flag leaf ligule, more hairs on the flag leaf ligule and a thinner flag leaf than Reveille hybrid bluegrass. 'HB 329' has a longer flag leaf ligule, fewer hairs on the flag leaf ligule and a thicker flag leaf than HB129 hybrid bluegrass (Table 18).

'HB 329' has a shorter spikelet length and fewer florets/spikelets on both the first whorl and third whorl than HB 129 hybrid bluegrass and is similar to Reveille hybrid bluegrass in these traits (Table 17). 'HB 329' has longer glumes than HB 129 and Reveille hybrid bluegrass. 'HB 329' is shorter than Reveille and HB 129 hybrid bluegrasses (Table 19).

TABLE 19

Comparison of morphological traits of plant inflorescence - spikelets, florets, glumes - from panicles harvested from a field nursery and plant height in 2005 at The Scotts Company facility at Gervais, Oregon.

What is claimed is:

1. A new and distinct hybrid variety of (Texas bluegrass× Kentucky bluegrass)×Kentucky bluegrass plant, as herein illustrated and described and characterized by a moderately rapid establishment; a dark green, moderately dense turf; a wide leaf blade; moderately aggressive rhizome growth; a moderate level of cotton on the seed; and a low to medium-low seed yield potential.
